UNITED STATES PATENT OFFICE.

JOHN VODICKA, OF CHICAGO, ILLINOIS, ASSIGNOR, BY MESNE ASSIGNMENTS, TO CINCH MANUFACTURING CORPORATION, OF CHICAGO, ILLINOIS, A CORPORATION OF ILLINOIS.

CURTAIN FASTENER.

Application filed February 20, 1924. Serial No. 693,972.

My invention has particular reference to curtain fasteners adapted for use on automobiles though as will appear from the drawing and specification it is likewise adaptable to other uses. It is the object of the invention to provide a so-called snap fastener which will not disfigure the frame of the automobile when the curtains are not in place, which is easy and certain of manipulation and which will securely hold the curtains in place.

In the drawings accompanying and forming a part of this application, Fig. 1 is a diametrical section through a curtain fastener embodying my invention, parts being shown in elevation; Fig. 2 a face view of the member of the fastener attached to the curtain viewed from the outside; Fig. 3 a similar view from the inside of the curtain and Fig. 4 an end view of the socket or frame member of the fastener.

The socket or frame member of the fastener comprises a barrel 5 which may be cylindrical in form and which at its inner end is reduced as at 6 and given an angular form in cross section. A screw 7 having a head 8 of form corresponding to the reduced portion 6 of the cup or housing extends through the bottom of the latter at 9 and is secured in place by peening or pinching the barrel slightly over the head of the screw as at 10. The upper or outer end of the barrel is formed with an outwardly extending flat flange 11, the outer periphery of which is preferably hexagonal or octagonal and an annular catch member 13 is applied to said flange, the edge of the catch member being bent under the flange at 14 to secure the parts firmly together. The outer end of the barrel is thus provided with an angular head to which a wrench may be applied for the purpose of driving the screw 7 into the wood of the frame member in which the socket is imbedded. The annulus 13 projects inwardly and is given a slightly funnel shape at 15 the inner edge terminating in a bead 16. Within the barrel 5 is a follower 17 which is normally pressed outward against the bead 16 on the catch member by a spring 18 in the barrel. The follower 17 is formed with a cylindrical flange 19 to guide it in the barrel and also with a central boss 20

which normally projects through the opening in the annular catch for a purpose which will appear.

The curtain element of the fastener comprises a flexible cylindrical catch which is pressed into the annular catch of the socket, contracting sufficiently to clear the same and then expanding to interlock therewith. The 60 spring catch 21 comprises a flat annular base 22 and a generally cylindrical entering portion 23 which terminates in an outwardly projecting bead 26. The entering portion is split longitudinally into a convenient number of sections, here shown at 26, the slits 27 extending nearly to the base. The bead 26 on the end of the entering member is of slightly larger external diameter than the internal diameter of the bead 16 of the annular catch of the socket. Hence when the split entering member is forced against the annular catch of the socket the spring catch or entering member contracts to permit its bead 26 to pass the bead 16 and then expands to 70 normal diameter so that the beads are in locking engagement. The boss or projection 20 on the follower of the socket member, heretofore mentioned, is of a diameter to freely enter the spring entering member or catch 80 when the latter is in normal expanded condition but to prevent sufficient contraction of the entering member to permit the bead thereof to pass the bead 16 of the socket. Therefore when the entering member of the curtain element of the fastener is pressed into the socket the follower in the latter yields until the bead on the entering member passes the bead on the socket and then the follower is returned by its spring into contact with the 90 end of the entering member but with its boss 20 within the end thereof. The parts of the fastener are thus firmly locked together and the entering member cannot be withdrawn until the boss of the follower is forced out 95 of the end thereof so that the entering member may contract.

In order to expel the boss of the follower from the end of the entering member when the curtain is to be unfastened a plunger or push button 30 is mounted in the curtain member of the fastener, the inner end thereof extending within the resilient entering member or split barrel. A spring 33 sur-

rounds the plunger and bears at its inner end on a seat or shoulder 34 provided for this purpose by reducing the diameter of the inner portion of the split barrel. The other 5 end of the spring bears against a collar 35 formed on the push button or plunger.

The housing for the operating elements of the curtain member of the fastener comprises a back plate 36 against which the flange 22 10 of the locking member rests and a concavo-convex front plate 37 the outer edge of which is turned over or upset at 38 about the edge of the back plate 36 thus firmly locking the two plates together and fixing the locking member. The front plate is formed with an opening 39 through which the end of the push button extends and which is engaged by the flange 35 on the push button or plunger to limit its outward movement. The back 15 plate 36 is formed with a rearwardly extending sleeve 40 which surrounds the entering member for a portion of its length. A washer 41, preferably of the shape shown, is furnished with the fastener and in applying the latter to the curtain 42 the curtain is pierced, the sleeve 40 projected through the opening, the washer 41 applied over the sleeve and the end 43 of the sleeve upset or bent back over the inner edge of the washer.

20 The socket member is applied to the frame by boring a hole or recess in the latter which will receive the body of the socket but fit the same snugly and then by the use of a wrench on the outer end of the socket driving the attaching screw thereof home. To secure the 25 respective members of the fastener together they are brought into registry and a slight pressure is sufficient to drive the entering member home when parts assume the position shown in Fig. 1. To separate the members of the fastener the push button is pressed in to drive back the follower of the socket after which the entering member may be 30 readily withdrawn. In actual use the thumb 35 is inserted under the edge of the curtain and a finger pressed on the push button so that by single movement of the hand the parts may be separated.

I claim:

30 1. In a curtain fastener, a socket member having an inwardly extending engaging portion, an open-ended contractible entering member adapted to enter the socket member and engage the engaging portion, a spring 35 pressed follower in the socket member movable longitudinally thereof and having a portion adapted to fit within the open end of the entering member and prevent contraction thereof and means in the entering member forcing the spring-pressed follower out of engagement with the entering member.

35 2. In a fastener of the class described, a socket member having an inwardly extending engaging member, an open-ended contractible entering member, a spring-pressed follower

in the socket member and movable longitudinally thereof having a portion fitting within the open end of the entering member to prevent contraction thereof, and a plunger 70 in the entering member and movable longitudinally thereof for pushing the follower out of engagement with the entering member.

3. In a fastener of the class described, a socket member having an inwardly extending annular catch, a follower movable longitudinally of the socket member, a spring normally forcing the follower against the catch, a resilient entering member adapted to be contracted to enter said catch and to expand to engage the latter in expanded and interlocking position, and a plunger movable independently through said entering member for forcing the follower rearwardly against the pressure of its spring.

4. In a fastener of the class described, a 85 socket having an annular, inwardly extending catch, a follower reciprocable longitudinally of the socket, a spring normally holding the follower in engagement with said catch, an entering member comprising a resilient 90 split portion adapted to extend through and interlock with the annular catch, a plunger in the entering member and movable longitudinally thereof and adapted to engage and press back the follower in the socket, and a 95 spring for normally projecting said plunger out of contact with the follower.

5. A separable fastener comprising a female member, a male member cooperating therewith comprising annularly arranged 100 spring tongues, a locking plunger within said female member and adapted to enter between said spring tongues to hold them against contracting movement, resilient means tending to force said locking plunger toward the male member, and an axially movable key within the male member arranged to impinge against the head of the locking plunger.

6. In a fastener of the class described, a 110 socket member having a contracted throat, a follower in the socket member adapted to seat against said throat and having a projection thereon extending into the throat when the follower is seated thereon, a spring 115 for seating said follower, an entering member comprising tongues adapted to extend into and engage within the throat and between the latter and the projection on the follower and axially movable means in the entering member adapted to force the follower away from the throat.

7. In a fastener of the class described, a socket and an entering member, the socket member having a contracted throat, and the entering member comprising resilient tongues having outwardly extending portions at their ends to engage said throat, means in the socket member adapted to enter between the tongues and lock them in throat-engaging 125 130

position and an axially movable plunger in the entering member for forcing the last said means out of locking position.

8. A separable fastener comprising an entering member and a socket member, the entering member presenting a contractible and expansible portion having an opening in one end adapted to be reduced in size when contacted with a socket member, the socket member having a casing provided with a front face portion having an engaging portion surrounding a stud-receiving aperture, a spring-pressed follower in the socket casing adapted to close the stud-receiving aperture when the entering member and socket member are disengaged and a locking portion provided by said follower for locking the entering member against contraction when the entering member is engaged with the engaging portion of the socket surrounding the stud-receiving aperture and axially movable unlocking means carried by the entering member and operable to displace the follower and permit separation of the fastener.
9. A fastener socket having a casing provided with a front face portion having an engaging portion surrounding a stud-receiving aperture for contracting the head of a resilient entering member and for receiving the same when the entering member is pressed against the socket adjacent the stud-receiving aperture, a spring-pressed follower enclosed within the socket casing and normally closing the stud-receiving aperture in the front face portion and a locking portion provided by

said follower for locking the entering member with the socket after the entering member has been first contracted then expanded to contact with the engaging portion of the socket.

10. A separable fastener comprising a stud member and a socket member, a hollow projection provided by the stud member, said hollow projection having spring means for detachably connecting said members together, axially movable spring-pressed locking means in the socket member for entrance into the hollow projection to lock said spring means in engagement with the socket member and means in the stud member extending into the hollow projection and operable to release the locking means from the hollow projection.

11. In a fastener of the class described, a socket member having a wall surrounding a stud-receiving aperture and a stud member comprising resilient tongues adapted to enter the stud-receiving aperture and engage the surrounding wall, an axially movable locking member carried by the fastener and adapted to enter between said resilient tongues and lock them in engagement with the said wall and adapted to retreat from locking position and means in the stud member having a portion projecting from that end of said stud member opposite the end which engages the socket member and operable to force the locking member out of locking position.

JOHN VODICKA.
